UNITED STATES PATENT OFFICE.

HANS HENRIK BLACHE, OF NEAR COPENHAGEN, DENMARK.

REGULATING DEVICE FOR FUEL-OIL PUMPS.

1,401,033.

Specification of Letters Patent. Patented Dec. 20, 1921.

Application filed September 18, 1919. Serial No. 324,681.

To all whom it may concern:

Be it known that I, HANS HENRIK BLACHE, citizen of the Kingdom of Denmark, residing near Copenhagen, have invented certain new and useful Improvements in a Regulating Device for Fuel-Oil Pumps, (for which I have filed application in Denmark April 30, 1918, application No. 1032/18,) of which the following is a specification.

In fuel-oil pumps for Diesel-engines and the like, there has been used, heretofore, a regulating device consisting of a rod or lever disposed below the suction valve and being connected to a centrifugal regulator or the like, the said lever being moved from the regulator and, thereby, causing the valve to be set down on its seat. In the heretofore used device, the regulating member (the rod or lever) was always connected to the valve and, by closing the valve at an earlier or later moment, it caused the engine to receive the quantity of fuel oil corresponding to the power yielded by the engine.

The present invention relates to a regulating device which acts, as did those heretofore known, by actuating the suction valve, but which, according to the present invention, is not in contact with the valve during the normal operation of the engine. During the engine's normal operation, the regulating device is entirely out of contact with the suction valve, so that the pump, in consequence thereof, will supply a full charge of fuel. Not until the regulator sets the regulating device in operation, will the latter engage the suction valve. In the pump, the regulation is effected by the suction valve being lifted during the downward stroke of the pump piston, so that the pump owing to the regulation supplies no fuel-charge or only a very small one.

The drawing illustrates one manner of constructing the invention.

Figure 1 shows the pump with the regulating device belonging thereto, in side-elevation and partly in section, and

Fig. 2 the pump viewed from the end in the direction of the arrow in Fig. 1.

a is the pump casing, wherein the suction valve *b* and the pressure valve *c* are provided. *d* indicates the plunger piston of the pump. The plunger *d* transmits its motion to a guided rod *h* connected to it by means of a lever *e*. The lever *e* is pivoted about the shaft *f*. In order to provide the necessary mobility there is inserted, between the

rod *h* and the lever *e*, a short link-member *g*. As it appears from the drawing, the rod *h* moves in the opposite direction from the plunger *d*. The rod *h* is fitted with a tappet *i* and a pawl *k* connected firmly to a heavy weight *l*. The pawl *k* with the weight *l* is rotatable about a pin *m* and is pressed, by means of the spring *n*, down into the position shown in Fig. 1 with full lines. The suction chamber of the pump is indicated by *o*. A rod *q* is inserted, through the stuffing box *p*, into the suction chamber and, when this rod is moved toward the left, it lifts the suction valve *b* from its seat. At the end of the pump, there is provided a shaft *r* fitted with two fixed arms *s* and *t*, the arm *t* being adapted to engage the pawl *k*, when the latter is in the position indicated by dot-and-dashed lines. When the pawl *k* is in engagement with the arm *t*, the shaft *r* will be turned, and the arm *s* will then push the rod *q* into the suction chamber *o*, so that the rod lifts the suction valve *b* from the seat.

The apparatus acts in the following manner:

As long as the rotary speed of the engine has not increased beyond the permissible limit, the spring *n* will be so powerful that the pawl *k*, notwithstanding the reciprocating motion of the rod *h*, will continue to remain in its bottommost position, or nearly there. The tappet *i* on the rod *h* will have turned the arm *t* out into the position shown on the drawing, where the arm will remain in consequence of the friction in the links and in the stuffing box *p*. In this position of the rod *q* there is left, between the latter and the suction valve, a small clearance allowing the suction valve to rest firmly on its seat and to operate like an ordinary suction valve for the fuel-oil pump, so that the latter admits a full charge of fuel to the engine.

If the rotary speed of the engine increases beyond the limit allowed, the acceleration of the reciprocating heavy weight *l* will become so great that it overcomes the pressure from the spring *n*. The accelerating forces are greatest at both dead centers, and the consequence thereof is that the weight *l* will swing outward to the right in Fig. 1, when the sliding rod is in its extreme position and begins to move inward toward the pump. When the weight *l* swings to the right, the pawl *k* is lifted upward, so that its knife-

shaped corner *u* will engage the corresponding notch *v* in the arm *t*. While the rod *h* now moves to the left, the pump piston travels to the right. During this motion, 5 the pawl *k* will turn the arm *t* and, thereby, the arm *s* to the left. Hereby the rod *q* is pushed into the oil-chamber *o*, where it lifts the suction valve *b* from its seat, so that the charge of oil drawn into the fuel- 10 oil pump during the suction stroke will be pressed back again into the oil chamber by way of the suction valve, so that no oil or nearly none is pumped into the cylinder or cylinders. When the rod *h* has reached its 15 extreme position to the left and again moves to the right, the arm *t* will remain in its position until the tappet *i* on the rod moves the said arm back into the position shown on the drawing. By the rod's motion to the 20 right, the pawl *k* becomes free, so that the acceleration on the weight *l* during this motion will swing the pawl back, that is downward. During the motion, the acceleration is assisted by the pressure from the spring *n*. 25 During a stroke as the one described, the pump will not have supplied any oil, and the cylinder will therefore not have developed any power. If the engine, in spite of the regulation, continues to run too fast, 30 the regulation will be repeated.

The above described regulating device may be used for multi-cylinder internal-combustion engines with one oil pump for each cylinder. This is indicated on Fig. 2 which 35 shows, in end-view, a multi-cylinder oil pump of this kind. The shaft *r* extends along all the pumps and supports the lever-arms *s* which operate simultaneously through the rods *q* to lift the suction valves in the 40 pumps exactly as above described. There is provided only one arm *t* at the end of the shaft *r*, and this arm *t* is actuated, during the regulation, in the above described manner by a pawl *k* fitted with a weight *l* and 45 placed on the rod *h* (Fig. 2). When the pawl *k* engages the arm *t*, all the arms *s* on the shaft *r* will be swung toward the pump, so that the suction valves of the corresponding 50 pumps will be lifted.

The device is especially suitable for marine engines, which ordinarily have 6 to 8 or more cylinders. In such motors, it will be very suitable to let the regulation act on only a smaller number of cylinders. The 55 regulation is only to become operative in case the ship lifts the propeller out of the water, the number of revolutions of the engine being otherwise regulated directly by hand, through a special apparatus actuating the suction valves of the pumps. 60 When the propeller is lifted out of the water, the regulation if performed on all the cylinders, will have the effect that none of these will produce any work, and the number of 65 revolutions of the engine will then be de-

creased too much, so that it will be difficult for it to be speeded up again, when the screw is again below water. For this reason, the regulation is omitted on one or more of the cylinders, so that the latter continue to 70 generate power, even if the other cylinders are set out of operation. This construction is indicated in Fig. 2, where there is shown a six-cylinder pump whose cylinders are marked with the numerals 1 to 6. The cylinders 2 and 3 are not regulated and will therefore continuously pump fuel into the corresponding cylinders of the engine. Opposite the pump cylinders 1, 4, 5 and 6, 75 there are provided arms *s* lifting the suction valves, when the pawl *l* engages the arm *t*, so that the said four pump cylinders are rendered non-operative. 80

On the drawing, the pump is shown as a pump with horizontally moved plunger 85 or plungers, respectively, but it may, without deviation from the principle underlying the invention, be built as a vertically disposed pump where the regulating members may be located, for instance, below the 90 pump.

I claim as my invention: —

1. Regulating mechanism for fuel-oil pumps, comprising in combination a member for unseating the suction valve of the pump, a lever system for operating said unseating member, a weight-actuated element movable back and forth and normally free of engagement with the lever system during its movements, but engageable under predetermined 100 conditions with said lever system to operate the same, and a tappet movable back and forth with said weight-actuated element to return the lever system to its initial position. 105

2. Regulating mechanism for fuel-oil 110 pumps, comprising in combination a member for unseating the suction valve of the pump, a lever system for operating said unseating member, a reciprocatory rod movable in juxtaposition to the lever system, a weight-actuated element pivoted to said rod for bodily movement therewith and for swinging movement relative thereto, said element being normally disposed out of range of the 115 lever system during its movements with the rod, but adapted to swing into position to engage and operate said lever system under predetermined conditions, and a tappet rigidly connected to said rod to return the lever system to its initial position. 120

3. In combination with a multi-cylinder pump, each cylinder of which has a suction valve and an unseating member therefor; a lever system embodying a rock shaft, a set of arms thereon for operating the unseating members of solely a few of the pump cylinders to the exclusion of the remaining cylinders, and an actuating arm fixed to said shaft; a weight-actuated element movable back and forth and engageable under pre- 125 130

determined conditions with said actuating arm to operate the lever system; and a tap-pet movable back and forth with said weight-actuated element to engage said actuating arm and thereby return the lever system to its initial position.

4. In combination, a valve; a controlling member therefor; a lever system for operating said member; and a reciprocatory weight-actuated pawl normally movable back and forth in a path out of range of the lever system, but adapted to rock automatically, under predetermined conditions, into a position in which its path of movement intersects said lever system so as to engage and operate the same.

5. In combination, a valve; a controlling member therefor; a lever system for operating said member; a reciprocatory weight-actuated pawl normally movable back and forth in a path out of range of the lever system, but adapted to rock automatically, under predetermined conditions, into a position in which its path of movement intersects said lever system so as to engage and operate the same; and means for restoring the lever system to its initial position after having been operated.

6. In combination, a valve; a controlling member therefor; a lever system for operating said member; a reciprocatory rod movable in juxtaposition to the lever system; a pawl pivoted to said rod for bodily movement therewith and for swinging movement relative thereto; a spring for normally holding the pawl in inactive position with relation to the lever system during its movements with said rod; said pawl being movable automatically, under predetermined conditions, into position to engage and operate said lever system; and means for restoring the lever system to its initial position after having been operated.

7. In combination, a valve; a controlling member therefor; a lever system for operating said member; a reciprocatory rod movable in juxtaposition to the lever system; a pawl pivoted to said rod for bodily movement therewith and for swinging movement relative thereto; a spring for normally holding the pawl in inactive position with relation to the lever system during its movements with said rod; said pawl being movable automatically, under predetermined conditions, into position to engage and operate said lever system during the movement of the rod in one direction; and a projection on said rod adapted, during the return movement of the rod, to engage and restore said lever system to initial position.

8. In combination, a valve; a controlling member therefor; a bell crank lever, one arm of which is operatively related to said controlling member; and a reciprocatory element movable back and forth in juxtaposition

position to the other arm of said lever; said element normally occupying a position in which it is inactive with relation to the last-named lever arm during its reciprocatory movements, but adapted to automatically assume a position, under predetermined conditions, in which it can engage and rock said last-named lever arm.

9. In combination, a valve; a controlling member therefor; a bell crank lever, one arm of which is operatively related to said controlling member; and a weighted pawl movable back and forth in juxtaposition to the other arm of said lever; said pawl normally occupying a position during its movements in which it is inactive with relation to the last-named lever arm, but adapted to automatically assume a position, under predetermined conditions, in which it can engage and rock said last-named lever arm.

10. In combination, a valve; a controlling member therefor; a bell crank lever having one arm operatively related to said controlling member; a reciprocatory rod movable in juxtaposition to the other arm of the lever; and a pawl pivoted to said rod for bodily movement therewith and for swinging movement relative thereto; said pawl normally occupying a position in which it is inactive with relation to the last-named lever arm during its movements with said rod, but adapted to swing automatically, under predetermined conditions, into a position in which it can engage and rock said last-named lever arm.

11. In combination, a valve; a controlling member therefor; a bell crank lever having one arm operatively related to said controlling member; a reciprocatory rod movable in juxtaposition to the other arm of the lever; a weighted pawl pivoted to said rod for bodily movement therewith and for swinging movement relative thereto; a spring normally holding said pawl in inactive position with relation to the last-named lever arm during its movements with said rod; said pawl adapted to swing automatically, under predetermined conditions, into a position in which it can engage and operate said last-named lever arm when said rod moves in one direction; and means engageable with said last-named lever arm during the return stroke of the rod to restore the lever to initial position.

12. In combination with a multi-cylinder pump, each cylinder of which has a suction valve and an unseating member therefor; a lever system embodying a rock shaft, a set of arms thereon for operating the unseating members of solely a few of the pump cylinders to the exclusion of the remaining cylinders, and an actuating arm fixed to said shaft; and a weight-actuated element movable back and forth and normally free of engagement with said actuating arm during

its movements, but engageable automatically with said actuating arm under predetermined conditions to operate the lever system.

13. Regulating mechanism for fuel-oil pumps, comprising in combination a member for unseating the suction valve of the pump; a lever system for operating said unseating member; a reciprocatory element movable in juxtaposition to the lever system at a speed directly proportional to that of the engine; and a pawl carried by said reciprocatory element to move bodily therewith

and to swing relatively thereto, said pawl occupying a position in which it is out of range of the lever system when the engine is 15 running at normal speed, but adapted to rock automatically under centrifugal force, when the speed of the engine becomes excessive, into a position in which it can engage and operate the lever system. 20

In testimony whereof he affixes his signature.

HANS HENRIK BLACHE
